UNITED STATES PATENT OFFICE.

LEON REES, OF LONDON, ENGLAND, ASSIGNOR TO MONROE M. SCHWARZSCHILD, OF NEW YORK, N. Y.

DESIGN FOR A DOLL-HEAD.

43,159.

Specification for Design.

Patented Oct. 15, 1912.

Application filed August 3, 1912. Serial No. 713,195. Term of patent 3½ years.

To all whom it may concern:

Be it known that I, LEON REES, a subject of the King of Great Britain, residing at London, England, have invented a new, original, and ornamental Design for a Doll-Head, of which the following is a specification, reference being had to the accompanying drawing, forming part thereof.

The figure is a plan view of a doll head, showing my new design.

I claim:

The ornamental design for a doll head as shown.

LEON REES.
